(57) **CLAIM**

The ornamental design for a ball point pen, as shown and described.

DESCRIPTION

FIG. 1 is a perspective view of the new design for a ball point pen;

FIG. 2 is a right side view thereof;

FIG. 3 is a left side view thereof;

FIG. 4 is a front view thereof;

FIG. 5 is a rear view thereof;

FIG. 6 is a bottom view thereof;

FIG. 7 is a top view thereof;

FIG. 8 is a right side view of the ball point pen of FIG. 1, shown in a state of use;

FIG. 9 is a right side view of the ball point pen of FIG. 1, shown in another state of use; and,

FIG. 10 is a right side view of the ball point pen of FIG. 1, shown in yet another state of use.

The dash-dash broken lines illustrate portions of the ball point pen that form no part of the claimed design. The dot-dash broken lines define the bounds of the claimed design and form no part thereof.

1 Claim, 6 Drawing Sheets
